DIELECTRIC WAVE GUIDE CLOSURE

Charles A. Rosencrans, Haddonfield, N. J., assignor to Radio Corporation of America, a corporation of Delaware

Application May 13, 1948, Serial No. 26,772

7 Claims. (Cl. 250—33.63)

1

This application refers to waveguides, and more particularly to means for mechanically closing an open or radiating portion of a waveguide with a dielectric closure.

It is often desirable to utilize a waveguide having an open end or mouth from which electromagnetic radiation is propagated after passage through the guide. Frequently the radiation is transmitted into open space and it is often further desirable that the waveguide portion from which the radiation is transmitted be located in the open air where it is susceptible to the deteriorating influence of the weather. Furthermore, if the waveguide is to handle large amounts of power, it is frequently desirable that it be pressurized, that is, that the interior of the waveguide be filled with certain gases above atmospheric pressure, whereby the moisture of the gas within the waveguide is controlled and is kept below a value at which the waveguide might 20 spark due to the large amounts of power being carried through it. Sometimes it is desired that the waveguide be evacuated for the same reason that one is pressurized, namely, to keep the performance of the guide independent of ambient weather conditions and to protect the interior of the guide, which may be coated with a precious metal, from the deteriorating effects of the atmosphere. There is presented, simultaneously with the problem of mechanically closing the 30 guide, the problem of electrically matching the waveguide proper and open space or the space into which the open portion of the waveguide radiates. It is necessary, of course, that the mechanical closure for the waveguide permits the guide to remain open insofar as electromagnetic radiation is concerned, that is, that the closure be mechanically effective and microwave transmissive. Accordingly, it has been the practice heretofore to close the end of the waveguide with a window of mica or the like which is transparent to electromagnetic radiation and to accomplish matching by metal "windows" or the like placed in the guide at proper points therein, so that the impedance of the waveguide is matched to the 45 impedance of outer space or the space into which the guide radiates, for the particular opening and guide being used.

It is an object of the present invention to provide a mechanical closure for a waveguide which is transmissive to electromagnetic radiation and simultaneously is effective to match the waveguide through the particular opening being used for the transfer of electromagnetic energy between space within and space outside the waveguide.

2

It is a further object of the invention to provide such a closure which is broad band in effect, that is, which matches the waveguide and the space into which it opens over a comparatively large band of frequencies.

It is a still further object of the invention to provide such a closure which gives a more effective impedance matching effect than has been heretofore possible.

It is a further object to provide such a closure for a rectangular guide which matches the guide to open space.

In accordance with the invention, I provide a closure made of dielectric material which is preferably characterized by comparatively low high frequency loss. The closure is tapered on the side remote from the waveguide opening to provide impedance matching. Preferably the tapered edge has a notch in it. It is preferable to bevel the edges of the closure on the other side opposite the tapered portion and next to the guide opening. I have found it possible by this means to provide a closure which gives a better broad band matching and at the same time provide a better mechanical closure for the guide which is more sturdy and more reliable than the closures previously employed.

Other objects, advantages, and novel features of the invention will be apparent from the following description and the accompanying drawing, in which:

Figure 1 is a perspective view of a closure element of the invention; and

Figure 2 is a plan view of the closure in the waveguide, the latter being shown partly in section for clarity.

Referring now to Figures 1 and 2 of the drawing, in which like parts bear like reference numerals, a rectangular waveguide 10 has broad 40 parallel walls 12 and 14 and narrow parallel walls 16 and 18. The waveguide is proportioned in conventional manner to transmit energy over a certain band of frequencies in the T. E.01 mode with the electric vectors perpendicular to the broad walls, as is well known in the art. The open end or mouth 20 of the waveguide has the broad walls 12, 14 extending somewhat farther from the waveguide than the narrow walls 16, 18, which are terminated in advance of the termination of the broad walls 12 and 14. Thus portion 22, of the broad wall 14, is brought beyond the termination of the narrow walls 16, 18 by beveled portions 24, 24', and then terminated in a common plane with that of broad wall 12 (which is similarly extended beyond the termination of narrow walls 16, 18) transverse to the waveguide.

axis. The closure member 30 is inserted in the waveguide, a short distance from the mouth 20, and has a portion 31 rectangular in a cross-section normal to the axis. Portion 31 has planar surfaces 32, 34 which are fitted respectively against the internal surfaces of the board walls 12 and 14. The portion 31 has planar side surfaces 36, 38 which are fitted against the internal surfaces of the narrow walls 16, 18. On the side of portion 31 away from mouth 20 the block 30 has a tapered portion 40 which is smoothly tapered with the axis of the waveguide and with no diminution of the dimension between the surfaces 36, 38. The tapered portion 40 terminates in what might be characterized as a knife edge 42 having a notch 44 centrally located thereof. On the side of portion 31 facing the opening or mouth 20, block 30 has beveled edges 46, 48 which are perpendicular to the broad walls 12, 14 and terminate at rectangular surface 50 which extends completely between the broad walls 12, 14 but does not extend completely between the side walls 16, 18. I find that best results are obtained if the over-all axial length of block 30 exceeds several wave lengths, and if the distance from surface 50 to the plane in which walls 22, 24 terminate is about one-eighth free space wave length, at the center frequency of the desired operating frequency.

In operation it is found that a matching impedance is obtained by a certain length of the tapered portion 40 and also by the size and depth of the notch 44 as well as by the beveled edges 46, 48. I have found that the notch 44 permits "fine" adjustment of the matching effect, so that standing waves in the guide may be brought to a minimum. The block 30 is preferably formed of a low loss dielectric material, for example, polystyrene and is readily fabricated of one piece and may be easily inserted through the open end or mouth 20 of the waveguide and sealed therein a short distance from the mouth. If a hermetical seal is not required or desired, for example, as in some pressurized waveguides where small gas escapage is permitted or desired, a press-fit or tight fit may be sufficient without a sealing fit. It will be understood, of course, that the distance from the mouth 20 also affects the match to be made, as well as the dielectric constant of block 30. I have found that the closure block 30 provides a broad band match which is much better and broader than those matching devices heretofore used, and which gives a much better control over the closeness of the matching. It will be understood, of course, that the waveguide is equally well matched for reception purposes from outer space as for the purpose of transmission by electromagnetic energy into the outer space from the mouth 20.

The following explanation of the effect of the closure herein described is probably the correct one, in so far as I currently have had an opportunity to investigate the action of the closure. The tapered edge of the closure provides a gradual transition from the interior of the waveguide to the dielectric filled portion thereof. This gradual transition is aided by the fact that the energy propagated in the guide, assuming that the energy is traveling from the interior of the guide to the exterior, first meets the transition element at portions where the electric field vectors are smaller in amplitude, that is, near the narrow walls of the rectangular guide in this instance. Thus, in a manner of speaking, the dielectric appears to the advancing electrical energy as a "smooth" transition. Moreover, be-

cause the length of the tapered portion is several wave-lengths it is believed that the broad-banding result is better than an abrupt transition. On the other side of the guide, there is necessarily an abrupt transition from the waveguide itself to the outer space, and this is matched by the suitable beveling of the edges of the dielectric element. This beveling is in the described embodiment, identical with the beveling of the broad walls at their termination. I have found that the most critical feature in obtaining a good impedance match is the spacing from the mouth, which probably varies somewhat with the dielectric constant of the dielectric material used. Furthermore, the notch aids the broad-banding effect because, qualitatively speaking, the energy enters the dielectric medium in a manner which is not linear with distance from the tapered edge along the axis of the guide, but at a rate which increases with distance from the tapered edge along the taper, to a greater degree than without the notch. With this closure element the guide can be matched to outer space with a selected opening, and it is not necessary to use the "horn" type openings to radiate to outer space. The latter openings have the disadvantage of restricting the radiation pattern to certain types of patterns which it is sometimes desired to avoid. Speaking still qualitatively and in a general way, the tapered notched portion matches the waveguide proper, and the beveled portion matches the beveled opening.

Not by way of limitation, but in order to enable those skilled in the art to duplicate the results I have obtained with a preferred embodiment and to build and use a closure of the new and improved type disclosed herein, the drawing shows the dimensions of the closure element in inches. Its spacing from the waveguide mouth and the dimensions of the guide mouth utilized will be apparent from the drawing. The operating frequency in the embodiment illustrated was about 7000 megacycles per second.

What is claimed is:

1. The combination of a waveguide having sidewalls and having an opening for the transfer of electromagnetic energy between the space within said waveguide and space outside the waveguide, and a closure and energy transfer matching element for said waveguide positioned entirely therewithin and having a first portion provided with sides fitted to said waveguide sidewalls, said element being of solid dielectric material and having an end portion closer to and an end portion more remote from said opening than said first portion, each of said end portions being progressively smaller in cross-section with axial distance from said first portion and said end portion more remote from said waveguide opening being axially longer than said end portion closer to said opening, said end portion more remote from said waveguide opening being tapered to a knife edge, said end portion closer to said waveguide opening having beveled edges.

2. The combination of a rectangular waveguide having a first pair of walls parallel to each other and a second pair of walls parallel to each other and normal to said first pair of walls for the transmission of electromagnetic energy within said waveguide with the electric vector normal to said first pair of walls, said second pair being separated by a distance affording transmission in the $TE_{0,1}$ mode at the operating frequency, and having an open mouth for the transfer of electromagnetic energy between the space within said waveguide and space outside

the waveguide, and a closure and energy transfer matching element for said waveguide positioned entirely therewithin and having a first portion provided with sides fitted to said waveguide sidewalls, said element being of solid dielectric material and having an end portion closer to and an end portion more remote from said opening than said first portion, each of said end portions being progressively smaller transversely with axial distance from said first portion, said end portion more remote from said waveguide mouth being tapered with dimensions thereof parallel to said second pair of waveguide walls progressively diminishing with axial distance from said mouth, the other said end portion closer to said waveguide mouth having beveled edges, the beveled surfaces of said beveled edges being substantially perpendicular to said first pair of waveguide walls.

3. The combination claimed in claim 2, said tapered portion being tapered to a knife edge substantially parallel to said first pair of walls.

4. The combination of a rectangular waveguide having a first pair of walls parallel to each other and a second pair of walls parallel to each other and normal to said first pair of walls for the transmission of electromagnetic energy within said waveguide with the electric vector normal to said first pair of walls, said second pair being separated by a distance to afford transmission in the $TE_{0,1}$ mode, at the operating frequency, and having an open mouth for the transfer of electromagnetic energy between the space within said waveguide and space outside the waveguide, and a closure and energy transfer matching element for said waveguide positioned entirely therewithin and having a first portion provided with sides fitted to said waveguide sidewalls, said element being of solid dielectric material and having an end portion closer to and an end portion more remote from said opening than said first portion, each of said end portions being progressively smaller transversely with axial distance from said first portion, said end portion more remote from said waveguide mouth being tapered with dimensions thereof parallel to said second pair of waveguide walls progressively diminishing with axial distance from said mouth, the other said end portion closer to said waveguide mouth having beveled edges, the beveled surfaces of said beveled edges being substantially perpendicular to said first pair of waveguide walls, said tapered end portion being tapered to a knife edge substantially parallel to said first pair of walls, said

knife edge being centrally located between said first pair of walls in said waveguide.

5. The combination claimed in claim 4, said knife edge having a notch centrally thereof.

6. A combination closure and energy transfer matching element for insertion entirely within a rectangular waveguide having an open mouth for the transfer of electromagnetic energy between the space within said waveguide and the space outside said waveguide, said element being of solid dielectric material and having a first portion provided with sides which fit the waveguide sidewalls on insertion therewithin to mechanically close the waveguide, and having end portions which, upon insertion, are axially closer to and more remote from said opening than said first portion, each of said end portions being progressively smaller transversely with axial distance from said first portion, said more remote portion being tapered to a knife edge, said knife edge having a notch centrally thereof.

7. A combination closure and energy transfer matching element for insertion in a waveguide having an opening for the transfer of electromagnetic energy between the space within said waveguide and space outside the waveguide, said element being of solid dielectric material and having a first portion provided with sides which fit the waveguide sidewalls on insertion therewithin to mechanically close the waveguide, and having end portions entirely within said waveguide axially closer to and more remote from said opening than said first portion, each of said latter portions being progressively smaller transversely with axial distance from said first portion, said end portions thereby being tapered, the tapered end portion more remote from said opening having a longitudinal notch therein.
